Primary Examiner — Abraham Bahta(74) *Attorney, Agent, or Firm* — Warner Norcross + Judd LLP(57) **CLAIM**

The ornamental design for a chair as shown and described.

DESCRIPTION

FIG. 1 is a front perspective view of a chair embodying the new design;

FIG. 2 is a rear perspective view of the chair;

FIG. 3 is a right side view thereof;

FIG. 4 is a left side view thereof;

FIG. 5 is a front view thereof;

FIG. 6 is a rear view thereof;

FIG. 7 is a top view thereof; and,

FIG. 8 is a bottom view thereof.

FIGS. 1–8 show portions of the chair in broken lines. The portions shown in broken lines are for environmental purposes only and form no part of the claimed design.

1 Claim, 8 Drawing Sheets(56)
